9 Claims. (Cl. 233—7)

This invention relates to a clarifying centrifuge for separating a suspension into liquid and solid, having a solid-surface drum forming the external boundary of a separating chamber, on the inner surface of which drum the solid is deposited, while the clarified liquid is discharged internally.

The known continuously operating clarifying centrifuges are generally constructed, in the case of the cylindrical form of the solid-surface drum, as scraper-type overflow centrifuges, and in the case of the conical form of the solid-surface drum as worm type centrifuges. In the former, continuous operation has to be interrupted for a short time, when the drum is filled almost to the overflow edge of the drum with solid, to scrape the latter out. In the worm type centrifuge, a conical conveyor worm rotates in the conical solid-surface drum at a different speed therefrom for conveying the solid, deposited on the inner surface of the drum, to the tapered discharge end of the drum, while the supernatant liquid is discharged at the wide drum end.

In scraper-type overflow centrifuges, the batch-wise discharge of the solid is disadvantageous. Under comparable working conditions, however, its clarifying effect is better than that of the worm type centrifuge. It is true that the worm type centrifuge permits extensive drying of the solid, provided the solid matter content of the feed suspension is not too low, owing to the stirring effect of the conveyor worm, however, the discharge liquid is, as a rule, still relatively turbid and requires further clarification treatment.

It is the object of the invention to provide a clarifying centrifuge which operates continuously and in addition allows good separation of liquid and solid to be achieved. In a clarifying centrifuge of the hereinbefore described kind, for this purpose the solid-surface drum is formed conically widened and the separating chamber is subdivided in the axial direction into two or more separating chambers, through which the suspension flows successively, subdivision into the chambers being effected by partitions extending at least to the vicinity of the wall of the solid-surface drum, said partitions having a bottom discharge situated on their outer edge for the deposited solid, and an overflow, situated closer to the axis of the centrifuge than the bottom discharge, for the suspension or clarified liquid.

Constructional examples of the subject of the invention are shown in simplified form in the drawing.

FIG. 1 shows an axial section through a clarifying centrifuge,

FIG. 1a is a top plan view of the internal parts of a clarifying centrifuge similar to that shown in FIG. 1, but employing separate bearing rings connected with each partition,

FIGS. 2 and 3 show axial sections through further embodiments,

FIG. 4 shows a portion of an axial section through a particular embodiment of a partition, and

FIG. 5 shows an axial section through a further embodiment.

The clarifying centrifuge shown in FIG. 1 has a rotor comprising a flaring solid-surface drum 1, which is

mounted by means of a shaft 2, secured to its narrow end, in a housing 3, and forms the outer boundary of a separating chamber 4. A stationary feed pipe 5 is arranged concentric with regard to the solid-surface drum 1 and extends from the side opposite the shaft 2 into the solid-surface drum 1 as far as into the vicinity of its narrow end.

The separating chamber 4 of the flaring solid-surface drum 1 is subdivided in the axial direction of the centrifuge by partitions 6¹, 6², 6³ into three separating chambers 4¹, 4², 4³. The partitions 6¹, 6², 6³ leave between their outer boundary and the inner surface of the flaring drum 1 an annular gap 7¹ or 7², 7³ serving as a bottom discharge for the deposited solid matter and have an overflow 8¹ or 8², 8³ situated closer to the axis of the centrifuge than said bottom discharge. A tubular support 9 connects the partitions 6¹, 6², 6³ together and by means of cross-pieces 9¹ to a bearing ring 10. A discharge funnel 11 for the liquid overflowing at 8³ is secured to the partition 6³. By movement of the bearing ring 10 by means of a block 13 engaging its annular groove 12 in the axial direction of the centrifuge, the flow cross section of the annular gap bottom discharge 7¹, 7², 7³ can be adjusted.

The shaft 2 is adapted to be driven by means not shown, so that the solid-surface drum 1 with the bearing ring 10 and the partitions 6¹, 6², 6³ rotate about the axis of the centrifuge.

The suspension to be separated into liquid and solid passes through the feed pipe 5 into the first separating chamber 4¹ and forms a ring, rotating with the solid-surface drum 1, in which the heavier solid particles travel outwardly, impinge on the inner surface of the flaring drum 1 and slide on the latter toward the bottom discharge 7¹. The lighter liquid and the solid particles suspended in it and not yet deposited flow over the overflow 8¹ into the second separating chamber 4², in which further solid particles are projected toward the inner surface of the drum 1. The material passing through the overflow 8² into the third separating chamber 4³ still contains solid matter in small quantity and in the form of very fine particles, which again are separated against the inner surface of the drum 1. The liquid, clarified in three stages in the drum 1, leaves practically clear, that is to say, without disturbing traces of solid, via the discharge funnel 11 and is collected in the discharge housing 14.

The solid particles separated in the separating chamber 4 slide along the inner surface of the drum 1 through the bottom discharges 7¹, 7², 7³ to the wide end of the flaring drum 1 and are discharged into a solid-matter collecting housing 15. The flow of solid over the inner surface of the flaring drum 1 is regulated by adjustment of the passage cross section of the bottom discharges 7¹, 7², 7³ so as to maintain a continuous stream of solid matter and so that the latter always fills the passage cross section of the bottom discharges, thus preventing the passage of free liquid through the bottom discharges.

On starting up the centrifuge, the bottom discharges 7¹, 7², 7³ are advantageously first closed entirely until a sufficiently large amount of solid matter has collected in front of them.

Instead of adjusting all three bottom discharges 7¹, 7², 7³, that is to say, all three partitions 6¹, 6², 6³, by means of a single bearing ring 10, each partition may be provided with its own bearing ring. For example, the partitions 6¹ and 6² may be slidable axially on the support 9, and each of these partitions may be connected by a ring of cross pieces 9¹ and 9² extending along generatrices of the support 9 with each of two further bearing rings 10¹ and 10² mounted on the shaft. See the bearing rings 10¹, 10² and 10³ illustrated in FIG. 1a. The cross pieces 9² of the partition 6² pass to the bearing ring 10² through

recesses in the partition 6¹ and recesses in the bearing ring 10², and the cross pieces 9¹ of partition 6¹ pass to the bearing ring 10¹ of partition 6¹ through recesses in the bearing ring 10². Like the cross pieces of the support 9, the cross pieces 9¹ and 9² of the partitions 6¹ and 6² would also pass through recesses in the hub disc of the solid-surface drum 1.

Adjustment of the partitions may be effected in accordance with the weight of the amount of solid matter situated in the separating chambers, the bearing rings being drawn by a spring into the position corresponding to the closure position of the partitions. If the amount of solid matter then increases the pressure on the partition also increases and the spring is tensioned, whereby the passage cross section of the bottom discharge is increased.

In the adjustment in common of the three bottom discharges 7¹, 7², 7³, as shown in FIG. 1, adjustment of the bearing ring 10 may also be effected in accordance with the quantity of solid matter discharged at the end of the solid-surface drum 1.

A vibration may be superimposed on the adjusting movement of the bearing ring 10 for preventing bridge formation of solid particles at the bottom discharge.

In the clarifying centrifuge shown in FIG. 2, there is connected to the flaring solid-surface drum 201, having two separating chambers 204¹ and 204², a solid-surface drum 216, which is conical in the opposite sense of the drum 201. In the drum 216 there is provided a conveyor worm 217 making a relative movement with regard to the drum 216. Said worm is connected externally to a solid-surface drum 218, arranged concentrically to the solid-surface drum 216 and mounted by means of a hollow shaft 219 in the centrifuge housing. The shaft 202 of the drum 201 and the hollow shaft 219 are adapted to be driven by means not shown.

Passing through the hollow shaft 219 is the feed pipe 205, fast with the centrifuge housing, for the suspension to be separated, as well as a discharge pipe 220 for the clarified liquid, which discharge pipe surrounds the feed pipe with spacing, and which is also fast with the centrifuge housing, and has a hollow disc-shaped liquid take-off device 221 at its end extending into the drum 201.

The solid matter issuing at the end of the drum 201 from the separating chamber 204 comes within reach of the conveyor worm 217, and is discharged by the latter through the free narrower opening of the drum 216 and is collected in a chamber 222. The clarified liquid running over the overflow 208² of the partition 206² leaves the centrifuge via the liquid take-off device 221, and the discharge path, confined by the annular space between feed pipe 205 and discharge pipe 220. The wall of the drum 218 may also serve as partition between solid and clarified liquid.

The shaft 202 carries a distributor head 223, rotating with it for the uniform introduction of the suspension into the first separating chamber 204¹.

In the clarifying centrifuge shown in FIG. 3, the throughput direction of the liquid in the separating chamber 304 is opposite to the throughput of the solid. As in the centrifuge according to FIGS. 1 and 2, the solid flows along the flaring solid-surface drum 301 and is pushed out by a conveyor worm 317 along the conical solid-surface drum 316.

The suspension to be separated into liquid and solid, however, is fed to the drum 301 through the feed pipe 305 at its wider end. The space limited outwardly by the abutting ends of the solid-surface drums 301 and 316 forms the first separating chamber, from which the liquid phase passes through the overflow 308² of partition 306² into the second separating chamber 304², and then through the overflow 308¹ of the partition 306¹ into the separating chamber 304¹, now counted as third separating chamber. The separating chamber 304¹ has an overflow 308, which is situated in the hub disc of the drum 301

and through which the clarified liquid is discharged into a discharge housing 324.

The shaft of the drum 301 is formed as a hollow shaft 325, and the drum 316 also has a hollow shaft 326, the centrifuge drum consisting of the drums 301 and 316 being journaled in the centrifuge housing by means of the hollow shafts 325 and 326. Journaled in the two hollow shafts 325 and 326 is a shaft 327 carrying the conveyor worm 317, said shaft 327 having a central bore 328 for the feed pipe 305 and orifices 329 for the exit of the fed suspension into the first separating chamber. The hollow shaft 325 and the shaft 327 are adapted to be driven at different speeds by means, not shown.

The partition 406 shown in FIG. 4 has an additional wall formed by an annular projection 430 for deflecting the overflowing liquid phase toward the drum 401. This additional wall is located opposite the overflow 408 and deflects outwardly the stream of liquid issuing from the opening of the overflow 408, whereupon the stream flows inwardly again around the outer edge of the additional wall 430. Such an additional wall, however, may also be provided in front in the throughput direction of the liquid. The gap between the inner surface of the drum 401 and the additional wall 430 must be larger than the thickness 25 of the layer of solid matter situated on the drum 401 in the region of the gap.

In the embodiment shown in FIG. 5, a scraper centrifuge is connected in front of the flaring drum 501. This scraper centrifuge has a substantially cylindrical solid-surface drum or annular shell 531, which forms a pre-separation chamber and is journaled in the centrifuge housing by means of a hub disc 532 and a shaft 533. This cylindrical solid-surface drum 531 carries on its end opposite the hub disc 532 the flaring solid-surface drum 501. The partitions 506¹ and 506² of the drum 501 are connected together by cross pieces 534, and to the bearing ring 510 via the discharge hopper 511 by means of a disc 535, cross pieces 536 and a disc 537. These parts 535, 536, 537 are located outside the two drums 501 and 531.

The suspension fed through the supply pipe 505 passes through a vertical duct 538 into the drum 531, the bulk of the solid matter being deposited on the inner surface of this drum. The liquid, still containing particles of solid matter, however, leaves the drum 531 via an overflow 539 directed toward chamber 504¹ at the narrower end of the flaring drum 501 and is completely clarified in the two successive separating chambers 504¹ and 504² of drum 501.

The solid matter collecting in the solid-surface drum 531 is periodically discharged in known manner by means of a scraping device 540, while the solid matter sliding on the inner surface of the solid-surface drum 501, regulated by the bottom discharges 507¹ and 507² and continuously being discharged, enters the solid-matter collecting housing 515.

The angle of flare of the wall of the drum is adapted to the angle of repose of the solid matter deposited in each case, and in the constructional examples, it increases from the first separating chamber to the second separating 60 chamber in the discharge direction of the solid matter.

What is claimed is:

1. A centrifuge rotor for separating a suspension into liquid and solid comprising a shaft; a flaring solid surface drum mounted on said shaft coaxially therewith; at least 65 two annular partitions arranged within said drum coaxially therewith; said partitions forming consecutive separating chambers for the suspension within said drum; each of said partitions leaving between its outer boundary and the drum a gap for the discharge of deposited solid along the inner drum surface toward the wider end of the drum and having an overflow for the liquid at a point situated closer to the drum axis than said discharge gap; means for supplying the suspension to the separating chamber situated nearest to the other end of said drum; and means for discharging 70 clarified liquid from the separating chamber situated near- 75

est to the other end of said drum; and means for discharging the deposited solid from the wider end of the flaring drum.

2. The combination defined in claim 1 in which at least one of said partitions is mounted axially shiftable in relation to the flaring drum, so as to allow the width of said discharge gap to be varied.

3. The combination defined in claim 2 in which at least two partitions are separately shiftable in the axial direction.

4. The combination in claim 1 in which the angle of flare of the drum increases in the solid discharge direction.

5. The combination defined in claim 1 in which the means for supplying the suspension are arranged to introduce the suspension into the separation chamber situated nearest to the narrower end of the drum.

6. The combination defined in claim 1 in which the means for supplying the suspension are arranged to introduce the suspension into the separation chamber situated nearest to the wider end of the drum.

7. The combination defined in claim 1 in which the means for discharging the deposited solid from the drum comprise a further flaring solid surface drum adjoining with its wider end the wider end of the first named drum;

and a conveyor worm arranged in said further drum so as to be rotatable in relation to said drum and to engage the solid matter issuing from said first named drum and to discharge it at the narrower end of said further drum.

5. The combination defined in claim 5 in which the means for supplying the suspension comprise an annular shell connected to the narrower end of the flaring drum, formed as a pre-separation chamber for receiving the suspension and having an overflow toward the narrower end of the flaring drum; scraper means being provided for the discharge of the solid matter deposited in said pre-separation chamber.

8. The combination defined in claim 1 in which at least one of said partitions is provided with an annular projection formed to direct the overflowing liquid outwardly toward the flaring drum.
